UNITED STATES PATENT OFFICE

HARVEY J. STEVENSON AND MERRILL KESSLER, OF LOS ANGELES, CALIFORNIA, AS-
SIGNORS TO NATIONAL MANICURING MACHINE CO., OF LOS ANGELES, CALIFORNIA,
A CORPORATION OF DELAWARE

DESIGN FOR A CASING FOR A MANICURING MOTOR

Application filed April 21, 1930. Serial No. 35,339. Term of patent 14 years.

To all whom it may concern:

Be it known that we, HARVEY J. STEVENSON, and MERRILL KESSLER, both citizens of the United States, residing in Los Angeles, in the county of Los Angeles and State of California, have invented a new, original, and ornamental Design for Casing for a Manicuring Motor, of which the following is a specification, reference being had to the accompanying drawings, forming a part thereof.

Figure 1 is a front elevation of a casing for a manicuring motor showing our new design;

Figure 2 is a top plan view thereof.

We claim:

The ornamental design for a casing for a manicuring motor, substantially as shown.
Los Angeles, California, April 15th, 1930.
